ROCKING CHAIR

David E. Ohman, Keene, N.H., assignor to
Hedstrom Co., Bedford, Pa.

Filed June 7, 1973, Ser. No. 367,741

Term of patent 7 years

Int. Cl. D6—01

U.S. Cl. D6—49

FIG. 1 is a perspective view from the front of a rocking chair embodying the new design;
FIG. 2 is a side view thereof; and
FIG. 3 is a top view thereof.

The side of the rocking chair not shown is the same as the side shown.

I claim:

The ornamental design for a rocking chair, substantially as shown and described.
